INVENTOR

MALVIN LICHTER

BY Walton Harrison,

HIS ATTORNEY.

UNITED STATES PATENT OFFICE.

MALVIN LICHTER, OF NEW YORK, N. Y., ASSIGNOR TO MALVIN LICHTER AND LOUIS JACOBS, PARTNERS, TRADING AS STICKLESS FAN COMPANY, OF NEW YORK, N. Y.

COMPOSITE COLOR PROCESS FOR PRINTING PICTURES.

Application filed June 19, 1923. Serial No. 646,294.

To all whom it may concern:

Be it known that I, MALVIN LICHTER, a citizen of the United States, and resident of New York, in the county of New York and 5 State of New York, have invented certain new and useful Improvements in Composite Color Processes for Printing Pictures, of which the following is a full, clear, and concise description.

10 My invention relates to the printing of colored pictures, and is especially adapted for use in connection with the system of printing of pictures by means of the well known three or four color half tone method 15 of reproduction.

However, my process may be also used to advantage in connection with the more expensive methods for printing pictures in a 20 large number of colors, and in a general way 25 may be considered as applying to composite color printing.

As is well known in this art the printing of pictures in colors has been carried to a high degree of refinement, and especially so 25 in some of the European countries. It is no unusual thing for a picture to be printed in as many as fourteen colors.

The system of printing pictures by means 30 of the three or four color half tone method of reproduction above mentioned is now used in this country to a considerable extent, on account of its cheapness as compared with the older systems using much larger numbers 35 of colors, but at the present stage of development the pictures printed with only three or four colors are, as a rule, somewhat inferior to those produced by the more elaborate and expensive systems, and employing colors in larger numbers.

40 Throughout a number of years of close observation, I have noticed that in actual practice pictures made in three or four colors, in the usual manner, are apt to present an appearance very suggestive of inferiority and cheapness, no matter how fine 45 may be the materials employed in doing the work, or how great the pains taken, or how much care may be used in the selection 50 of the scenes to be printed.

55 I have made the discovery, however, that I can print pictures by my composite color process, and using only three or four colors, to present to the eye of the casual observer the appearance of the finest and most expensive lithographic color printing; and to

present to the eye of even the trained expert a much better appearance than has heretofore been obtained by printing in a small number of colors. The manner in which I 60 accomplish this result is to incorporate in the picture a ground work, such as a stippled surface, a crayon work surface or a grained surface, or a number of such surfaces, so arranged as to simulate the corresponding 65 surface or surfaces usually present in color 70 pictures made by the elaborate and expensive lithographic processes which have been used from time immemorial upon color pictures of the finest kind. In other words I 75 find that in pictures printed in three or four 80 colors the inferiority is not due primarily to the fact that colors used are reduced to three or four in number, but is attributable mainly to the fact that the shades and shadows of the picture can not be brought out to advantage unless printed from plates carrying 85 shading made up of stippling or of crayon work or grain work or the like, so as to confer upon the picture the shading effects 90 peculiar to high grade lithographic color 95 printing.

More particularly stated, I make my pictures by the process of printing in three or four colors, but with this qualification, that in one or more of the printing plates used 85 for applying the respective colors, some or all of the shading surfaces are so formed as to print shading consisting of stippling, crayon work or grain work, as the case may be, so as to simulate the shading to be found 90 in pictures made by the elaborate lithographic color process.

Stating this feature a little more in detail, in making my plates for applying to the picture the colors to be used, say for example 95 the three primary colors yellow, red and blue, I provide at least one of these plates, preferably the one used for the red or the blue color, and in some instances both of these two plates, with relief or intaglio surfaces for printing shadows made up of either stippling, crayon work or grain work, as the case may be. This done, by the use 100 of the several plates for printing in succession the respective colors, the shading exhibited by the finished picture has an appearance closely simulating that of the finer 105 pictures.

I have made the further discovery that in 110 performing the steps just mentioned, it is

practicable to so form the surfaces of the printing plates that the shading applied thereby may be graded with great refinement as to the qualities known in this art as depth and solidity of colors, and that the different colors applied by the different plates may be scientifically blended at the various points where the shading carried by one of the printing plates may happen to coincide with the shading carried by another of the plates. The final result is that the finished pictures may exhibit shading which is accurately modulated as to strength of color and also as to progressive blending of two or more colors along a given portion of the picture. For instance the shading of the plate may be so proportioned and arranged that in the finished picture there may be a shade which at one point exhibits a predominance of red, and at another point exhibits a predominance of blue, and at intermediate points exhibits a successive gradation or gradual blending in color from red to blue. Again, the picture may exhibit a piece of shading of which one part has a composite color in which red predominates, this color gradually dissolving at short distances from the part just mentioned, another part of the same shading having a composite color in which blue predominates, this color also dissolving at short distances from the part in which the blue predominates. It is practicable to so distribute the shading surfaces carried by one or more plates as to vary within wide limits the relative intensity or coloring, and also the progressive change from one color to another. It is easy, by using good judgment and the experience obtained by practice, to so distribute the shading surfaces upon the printing plates as to enhance the appearance of the printed picture far beyond what could ordinarily be expected in a picture printed in three or four colors, in the manner well known in this art.

Before going further into the details of my improved process, I will for convenience refer briefly to the manner in which printing plates are now usually prepared for purposes of color printing.

Suppose that a particular picture, such as an oil painting, is to be copied. First a camera is placed in front of the picture, and is used in connection with a so-called color filter, so as to photograph those parts of the picture of which the predominant color is, say yellow. Next another filter is substituted, and a photograph is made of those parts of the picture of which the predominant color is, say, red. Lastly another filter is substituted, and another photograph taken, showing those parts of the picture in which the predominant color is, say, blue. From the photographs thus taken, usually either three or four in number according to

the number of colors, an equal number of printing plates are prepared. Since these printing plates necessarily follow the photos from which they are made, the result is inevitable that one of the plates makes a showing dependent upon the yellow color to be found in the oil painting, another makes a showing dependent upon the red color, and the showing made by another of the plates is dependent upon the blue color of the painting. It also follows that the showings made by the several plates must differ from each other as the distribution of the several colors in the oil painting differ from each other. Thus if the three plates thus prepared are used separately for making three impressions upon as many separate sheets of paper, the three impressions will differ from each other as to the distribution of lights and shadows, and also to some extent as to the contour of such visible objects as are fragmentarily shown by each of the respective plates, in so far as these objects may be discernible.

It is apparent, therefore, that at least one, and usually two, of the plates must be provided with shading surfaces in order that the finished picture shall disclose a shaded surface of the kind here contemplated.

Since it is hardly practicable to apply stippling, crayon work or grain work to a plate after the plate is practically finished, it is necessary that the shading be made photographically, and this must be done at the time when the photographs are taken, preparatory to making the plates therefrom.

What I do, therefore, is to prepare the original picture by placing upon it, either by hand or by any appropriate mechanical means, an adequate number and variety of 105 stipples, or equivalent crayon work or grain work, so as to produce in the original picture the shading effect here contemplated. In doing this I confer upon the original picture, however produced, more or less shading or ground work simulating that which is produced in the finest kinds of lithographic color pictures. I may make the shading in one or more colors, either by blending paints of two or more colors, or by interspersing stipples or crayon work characters of one color among stipples or crayon work characters of a different color. This done, when the several photographs are taken and the several color plates made 120 therefrom, one or more of these plates will thus be provided with shading derived from one of the colors used in shading the original picture, and another of the plates will exhibit shading derived from another of the colors used in shading the original. It stands to reason, of course, that the plates thus produced will differ from each other in appearance.

Reference is made to the accompanying 130

drawing forming a part of the specification, and in which like reference characters indicate like parts throughout all of the figures.

Figure 1 is a plan view of an impression 5 printed from a color plate made in accordance with my invention, for use in printing a three color picture, the color to be applied by this particular plate being yellow.

Figure 2 is a plan view of an impression 10 printed from another color plate for use in making the picture, this plate being for the purpose of applying the red color.

Figure 3 is a plan view of an impression 15 printed from the third color plate to be used in making the picture, and is adapted for the purpose of applying the blue color.

Figure 4 is a plan view of the oil painting 20 or other picture to be copied, and therefore is a similar view of the finished picture, which is an exact copy of the oil picture, the shading of certain areas being exaggerated and selected somewhat arbitrarily in order to render clear the principles of my invention.

25 A solid yellow color appears at 5, and at 6, 7, 8, 9 and 10 are spots or patches also of yellow, but differing in form and size, and also differing in the density or solidity of the coloring. At 11 there is no coloring, the 30 space thus left disclosing roughly in outline the representation of a dog's head.

In Figure 2 a solid red color is indicated at 12 and at 13, 14, 15, 16 at 17 and 18 are patches of the same color, differing from 35 each other in form and size, and also in the density of the coloring. At 20 and 21 are shown patches of shading, made up either of stiples or crayon work characters or of grain work as the case may be, and at 40 21^a and 22 are areas from which all color is absent.

In Figure 3 at 23 is shown a solid blue color, and at 24, 25, 26, 27, 28, 29 and 30 are patches of the same color, these patches 45 differing from each other in form and size as well as in the density of the color employed. At 31 no coloring is shown, and at 32, 33 and 34, there are patches of shading, for background effect. At 34^a there is no 50 color.

The coloring of the finished picture may be understood from Figure 4. At 35 is shown a solid but composite color, made by the overlapping of the yellow, the blue and the red. At 36, 37, 38, 39, 40, 41 and 42, are patches of composite coloring, these patches differing from each other in form and size, and also in the density of the coloring. There is no coloring at 43. At 44 55 is an area of shading, in which there predominates a composite color made by blending together red and blue. At 45 is an area of shading, of which the predominating color approaches blue. At 46 is a shading area of which the predominating color is

still nearer to true blue. At 47 is another shading area, the predominant color of which is red.

I will now explain how the various modulations of color are obtained in the finished 70 picture, as represented more particularly in Figure 4.

I will assume that the general ground work of the picture is of composite color, made by overlapping very light tints of yellow, 75 red and blue, and that the background thus produced is indicated at 35. Suppose now that upon the area 44 I apply by hand or by any convenient mechanical method a patch of stiples or crayon work, in which 80 the red and blue colors predominate. I can do this in either of two ways; that is, by applying red stiples, crayon work characters or grain work, interspersed with blue stiples, crayon characters or grain work, or 85 by applying stiples, crayon work or grain work characters each made of a mixture of red and blue. The shading, no matter how made, is relatively heavy in color as compared with the ground work 35. If the original 90 painting or other original picture thus prepared, as indicated at 44 in Figure 4, be now photographed as above described so as to filter out the three colors red, blue and yellow in the usual manner, the red and 95 blue must of course manifest themselves; and when the respective color plates are made as a result of these photographs, and impressions are thereafter printed from these plates, as indicated in Figures 2 and 3, 100 the red color originally present in the area 44 in Figure 4 will show up as indicated at 21 in Figure 2, and the blue color will show up as indicated at 21 in Figure 2. No corresponding indications will be made, however, in the yellow color shown at 5 in Figure 1. It stands to reason, therefore, that when the three color plates are used in printing a picture, and to this end three impressions are made in succession and corresponding to the impressions indicated respectively in Figures 1, 2 and 3, but caused to overlap or blend into a single picture as shown in Figure 4, the color effect of the area 21 in red in Figure 2, and the area 32 in blue in 110 Figure 3, will make the composite effect indicated at 44 in Figure 4.

Suppose, again, that in the original picture I apply at 45 a patch of stiples, crayon work characters or grain work, as the case 115 may be produced rather heavily in blue. The effect is that when the picture is photographed with its colors filtered as above described, and three color plates made accordingly as indicated in Figures 1, 2 and 3, the area 33, in Figure 3 will appear as shaded; but there will be no corresponding shaded area upon the corresponding part in Figure 1 or Figure 2. The final result must be that in the finished pictures the area 45 will 120

appear as a heavy blue, qualified by the general effect of a light background of red and yellow overlapping each other. Thus the shading at 45 in the finished picture will be of composite color, in which blue predominates.

Suppose, again, that in the original picture, I apply to the area 46 a patch of 10 stipples, crayon work characters or grain work in blue, upon a light yellow tinted surface, but that I carefully exclude all red. This being done, and the several successive steps of the process being executed as above described up to the point where the color 15 plates are finished and impressions taken therefrom so as to overlap each other, it follows that in the yellow impression contemplated by Figure 1 the yellow color will be uniform, while in Figure 2 there will be a 20 vacancy 21^a (practically a white spot), and in Figure 3 the area 34 will exhibit the stipples, crayon work or grain work. It follows that upon the entire showing made by all of the plates the area 46 in the finished 25 picture will show a shaded surface in blue, qualified slightly by the uniform yellow color extending throughout this same area, but not qualified by any red color.

Suppose, again, that the area 47 in Figure 4 be provided with heavy stipples, 30 crayon work characters or grain work made in red color upon a light yellow background, and the photographs taken and plates made accordingly as above described. An impression from the plate for printing the red 35 color will now show stipples, crayon work or grain work in red, as indicated in Figure 2, but the corresponding area 34^a in the impression made in blue, as indicated in Figure 3, will be blank, or in other words will 40 show simply as a white surface qualified by the light and uniform background of yellow. The net result is that in the finished picture the area 47 is shown as red, qualified 45 slightly by yellow.

It will be noted that the surfaces 6, 7, 8, 9 and 10 in Figure 1 vary from each other slightly in form, and also in depth and intensity of coloring. This is also true of the 50 surfaces 13, 14, 15, 16, 17, 18 and 19 of Figure 2, and the surfaces 24, 25, 26, 27, 28, 29 and 30 in Figure 3. The reason why the various surfaces thus differ from each other, both as to form or contour and as to intensity of coloring, is simply that the various 55 colors are so applied and distributed upon the original picture as may be understood by a careful study of the surfaces 36, 37, 38, 39, 40, 41 and 42 of Figure 4. Thus these 60 surfaces must show in the finished pictures very much like they show in the original oil painting or other picture to be copied.

It is to be understood that any of the surfaces just mentioned, or indeed any particular area of the oil painting or other picture

to be copied, may be provided with stipples, crayon work characters or grain work, either fine or coarse, light or heavy, in one or more colors. It will also be understood that for purposes of the shading here contemplated, I can use mixed colors or separate colors, as judgment and experience may decree to be the best, considering the character and quality of the work, the prices at which it is to be done, the distance from which the 75 finished pictures are to be viewed by the observer, the sizes of the pictures, etc.

I find it practicable to take a fine picture, preferably a well-executed copy of an oil painting or the like, and to add to this picture a considerable quantity of shading, made as above described, by applying to the picture the stipples, crayon work characters or grain work. This shading may be applied by hand or by any well known mechanical expedient suitable for the purpose, and as above indicated may be varied within wide limits as to colors and as to forms. This done, and the various steps being performed in the manner well known in this art 90 for printing pictures in composite colors, the finished pictures present to the eye of the observer the appearance of multi-color pictures made by expensive multi-color lithography.

I do not limit myself to the use of any precise mechanism nor to the exact steps above described for the purpose of carrying out in my invention, the scope of which is commensurate with my claims.

Having thus described my invention what I claim as new and desire to secure by Letters Patent is as follows:

1. The method herein described of producing copies of pictures printed in colors and improving the shading of said copies, which consists in taking a picture printed in colors, improving the shading of said picture by working upon the same by hand, and then producing, by aid of the half tone color process, copies of the original picture as a whole.

2. The method herein described of producing copies of pictures printed in colors and at the same time improving the shading of the copies, which consists in taking a colored picture, applying to the same as a distinct step a ground work representing shading, and copying said picture as a whole by aid of the half tone color process.

3. The method herein described of producing copies of pictures printed in colors and of improving the appearance of said copies as thus produced, which consists in taking a colored picture, applying to the same a ground work wrought in colors and representing shading, and producing by aid of colored photography copies of the original picture as thus treated.

4. The method herein described of print-

ing colored pictures, which consists in applying to a colored picture to be copied a colored ground work simulating the ground work of a picture produced by a multi-color 5 lithographic process, and then making copies, by aid of composite color photography of the original picture thus treated.

5. The method herein described of printing colored pictures, which consists in applying to a picture to be copied a ground work simulating the ground work of a picture produced by a multi-color lithographic process, then photographing the picture to be copied, making color plates from the photographs thus taken, and finally reproducing 10 from said color plates a colored reproduction of the original picture.

6. The method herein described of copying colored pictures having the appearance of fine lithographic printing, which consists in applying to a picture to be copied a ground work made up of stipples or crayon work 15

and wrought in colors so as to simulate the ground work of a picture produced by a multi-color lithographic process, and finally 25 making copies, by aid of color photography, of the original picture thus treated.

7. The method herein described of producing copies of pictures printed in colors and of improving the appearance of said 30 copies as compared with the original, which consists in taking a colored picture, applying to the same as a distinct step a ground work wrought in a plurality of different colors and representing shading, and then by 35 aid of composite color photography, making from the original picture thus treated copies in which said ground work is reproduced in its original colors.

Signed at New York, in the county of 40 New York and State of New York, this 17th day of February, 1923.

MALVIN LICHTER.
